R. N. WEST.
WASHING MACHINE CYLINDER.
APPLICATION FILED OCT. 26, 1921.

1,433,319.

Patented Oct. 24, 1922.

Inventor
Robert N. West

By Frank C. Cushing
Attorney

UNITED STATES PATENT OFFICE.

ROBERT N. WEST, OF BROOKLYN, NEW YORK, ASSIGNOR TO ADAMS LAUNDRY MACHINERY COMPANY, OF TROY, NEW YORK, A CORPORATION OF NEW YORK.

WASHING-MACHINE CYLINDER.

Application filed October 26, 1921. Serial No. 510,614.

To all whom it may concern:

Be it known that I, ROBERT N. WEST, a citizen of the United States, residing at Brooklyn, in the county of Kings and State of New York, have invented new and useful Improvements in Washing-Machine Cylinders, of which the following is a specification.

Reference may be had to the accompanying drawings, and the reference characters marked thereon, which form a part of this specification. Similar characters refer to similar parts in the several figures therein.

This invention relates more particularly to washing-machine-cylinders of the type commonly used in laundries for washing soiled articles of clothing.

Such cylinders are rotatively operated first in one direction and then in the opposite direction by means of suitable mechanism as is well understood in the art.

For this purpose the cylinder is provided with a shaft projecting from one of its ends to which shaft the driving power is applied by suitable mechanism.

This driving shaft is mounted upon the end or head of the cylinder by means of a supporting-plate which is bolted to the head of the cylinder.

The continued reversing movements of the cylinder soon causes these bolts to circularly elongate the holes in the head through which the bolts pass so that after a greater or less period of use the shaft-supporting plate ceases to be properly secured upon the head.

The principal object of the present invention is to relieve from this excessive strain the bolts whereby the shaft-supporting plate is secured to the head of the cylinder.

Fig. 1 of the drawings is an end view of a washing-machine-cylinder made in accordance with my invention.

Fig. 2 is a vertical section taken on the broken line 2—2 in Fig. 1.

Fig. 3 is a longitudinal section taken on the broken line 3—3 in Fig. 1.

Fig. 4 is a view in perspective of one of the clamp-plates detached.

Referring to the drawings wherein the invention is shown in preferred form, the cylinder is made up of four longitudinal ribs, 1, two heads, 2, only one of which is

shown, and staves, 3, interposed between neighboring ribs, 1.

These parts are usually made of wood, and the cylinder thus formed is rotatively mounted within a casing, 4.

In carrying out my invention, I extend the ribs, 1, beyond the head, 2, as shown at 1^a, in Figs. 2 and 3.

Upon the head, 2, I mount a shaft-supporting plate, 5, which is preferably secured to the head by bolts, 6, in the usual manner.

From the plate a shaft, 7, projects out through the neighboring end of the casing, 4, to receive the driving mechanism comprising in part a pinion, 8, fixed on said shaft whereby rotative movements in opposite directions can be imparted to the shaft.

The shaft-supporting plate, 5, is formed with abutments, 9, on opposite sides of, and spaced away from the projecting ends, 1^a, of the respective ribs, 1.

In the spaces thus provided between the abutments, 9, and the ends, 1^a, of the ribs, I apply to opposite sides of the respective rib-ends, 1^a, clamp-plates, 10, engaged by suitable screw-mechanism interposed between the clamp-plates and abutments 9.

The clamp-plates, 10, are made of metal and are preferably formed with spurs, 11, on their inner sides, which spurs are adapted to penetrate the ends of the wooden ribs.

Each clamp-plate is also preferably provided with a central aperture, 12, adapted to freely receive a screw-bolt.

As a preferred form of screw-mechanism for clamping the clamp-plates, 10, firmly upon opposite sides of the respective rib-ends, 1^a, I have shown a screw-bolt, 13, having an angular head, 14, seated in an angular recess, 15, formed in the neighboring side of the abutment, 9, the screw-end of the bolt being adapted to play freely in the aperture, 12, in the neighboring clamp-plate, 10, said screw-bolt having thereon a nut, 16, engageable with the outer side of said neighboring clamp-plate.

The recess, 15, in the abutment, 9, is preferably formed so as to prevent the bolt-head, 14, escaping outwardly from the recess as well as to prevent the bolt from rotating.

In assembling the device the nut, 16, is unscrewed to withdraw it from the screw.

end of the bolt a sufficient distance to permit the bolt and the neighboring clamp-plate to be interposed between the abutment, 9, and the neighboring rib-end, 1^a, after which the 5 nut, 16, is set up so as to drive and clamp said clamp-plate against the neighboring side of the rib-end, 1^a, thereby seating the spurs, 11, in the rib-end.

By means of my invention the thrust of 10 the shaft-supporting plate, 5, is transmitted directly to the ribs, 1, instead of directly to the head of the cylinder as heretofore.

The bolts, 6, are thus relieved of all or practically all of this thrust, and are relieved from the tendency to elongate the 15 holes through which they pass.

Lost-motion can at any time be readily taken up by means of the nuts, 16, so that there is no tendency for the parts to become worn by a relative movement between 20 the shaft-supporting plate, 5, and the cylinder as was the case where the thrust of the shaft-supporting plate, 5, was transmitted to the head of the cylinder by the bolts.

While I have shown and described the invention in its application to a washing-machine-cylinder, it is also applicable to any cylinder operated under similar conditions.

What I claim as new and desire to secure 30 by Letters Patent is—

1. In a device of the class described and in combination, a cylinder having a head, and a rib projecting beyond the head; a shaft-support secured to the head and formed with 35 abutments on opposite sides of and spaced from the projecting end of said rib; clamp-plates on opposite sides of the projecting

end of said rib; and screw-mechanism between the respective abutments and clamp-plates.

2. In a device of the class described and in combination, a cylinder having a head, and a rib projecting beyond the head; a shaft-support secured to the head and formed with abutments on opposite sides of and spaced 40 from the projecting end of the rib; apertured clamp-plates engageable with the opposite sides of the projecting end of the rib; screw-bolts having heads in non-rotative engagement with the respective abutments, the 45 inner ends of the bolts being freely movable within the respective apertures in the clamp-plates; and nuts fitting the respective bolts and engageable with the respective clamp-plates.

3. In a device of the class described and in combination, a cylinder having a head, and a rib projecting beyond the head; a shaft-support secured to the head and formed with abutments on opposite sides of 60 and spaced from the projecting end of the rib; apertured clamp-plates on opposite sides of the projecting end of said rib, said clamp-plates having rib-engaging spurs; screw-bolts having heads in non-rotative engagement with the respective abutments, the 65 inner ends of the bolts being freely movable within the respective apertures in the clamp-plates; and nuts fitting the respective bolts and engageable with the respective clamp-plates.

In testimony whereof, I have hereunto set my hand this 21st day of October, 1921.

ROBERT N. WEST.
